UNITED STATES PATENT OFFICE

FLETCHER D. GRUND, OF WESTON, OHIO, ASSIGNOR TO THE AMERICAN SWISS COMPANY, OF TOLEDO, OHIO, A CORPORATION OF OHIO

DOOR LATCH

Application filed June 13, 1929. Serial No. 370,494.

This invention relates to door latches, but more particularly to latches or fastening devices intended for automobile doors, and an object is to provide a simple and efficient door latch having the novel features of construction and arrangement hereinafter described.

The invention is shown by way of illustration in the accompanying drawings, in which:

Fig. 1 is a side elevation of a door latch; and

Fig. 2 is a transverse section on the line 2—2 of Fig. 1.

The illustrated embodiment of the invention comprises a door latch having a back plate 1 provided with a lip or flange 2 at one side. The flange 2 is formed with an opening 3, through which the head 4 of the latch bolt is slidable. The latch bolt is shown consisting of a plate 5 secured by rivets 6 to the head 4.

Holding the bolt plate 5 in place, is a cover plate 7 of relatively small size of approximately the width of the bolt plate 5. The opposite sides of the cover plate are bent downwardly and engage the back plate 1, openings being formed in the cover plate to receive tabs or tongues 8, which extend therethrough and are bent over to retain the combined cover and guide plate 7 in place.

The bolt 5 is formed with an elongate slot 9, and adjacent the end thereof remote from the head 4 are oppositely arranged inclined shoulders 10 (one above and one below the slot as shown in Fig. 1). The shoulders 10 are formed by pressing out the metal of the bolt plate to provide a depressed portion 17. Extending through the slot 9 and bearing in the cover plate and back plate members is a hub 11 having a polygonal opening 12, which extends therethrough. Oppositely extending arms 13 are provided on the hub 11, and are engageable with the shoulders 10, so that by turning the hub in either direction the bolt may be retracted for unlatching the door. As shown, the cover plate 7 is embossed at 14 to allow clearance for the inward movement of the bolt head 4, thereby to provide

a compact assembly without sacrificing features of strength and durability.

The bolt is normally held in projected position by a coil spring 15, one end of which is held at 16 to the case plate, and the opposite end bears against a shoulder 17^a on the outer side of the depressed portion 17.

The end portion of the bolt is provided with an extension 18, which is disposed in the plane of the forward portion of the plate 5. The extension 18 may be connected to any suitable retracting means, such as a remote control, by links and levers in any known manner. It will be apparent that bolt extension 18 not only serves to provide a connection for a remote control strap, or other inside retracting means, but also provides a keeper for the end of the spring 15, preventing the latter from becoming disengaged from the bolt. An extremely simple construction is produced by depressing a portion of the bolt plate, inasmuch as on one side retracting shoulders 10 are provided, and on the opposite side a spring engaging shoulder 17^a.

From the above it is apparent that the latch may be inexpensively manufactured due to the relatively small number of parts and ease of assembly, most of the parts being stampings which adapt it particularly for production. Numerous changes in details of construction and arrangement may be made without departing from the spirit of the invention.

What I claim as new and desire to secure by Letters Patent is:

1. A door latch including a case plate, a bolt slidable over said plate and having its rear end portion extended outwardly to provide a shoulder and then its terminal extended rearwardly to lie in spaced and substantially parallel relation to the plate to form an anchor for remote retracting means for the bolt, a spiral spring secured to the plate and having an end engaged with said shoulder and disposed in the space between the plate and said terminal of the rear end portion of the bolt, and means to operate the bolt.

2. A door latch including a case plate, a bolt slidable over said plate and having its

rear end portion depressed to provide a rear shoulder and front shoulders, means to retract the bolt engaged with the front shoulders, and a spiral spring secured to the plate and having an end engaged with the rear shoulder, said depressed part being located spaced from the rear terminal of the bolt so that the latter provides a stop restricting movement of said end of the spring laterally of the plate, and also a connection for remote retracting means for the bolt.

3. A door latch including a case plate, a bolt slideable over said plate and having its rear end portion depressed to provide a rear shoulder and front shoulders, a cover plate extending over the bolt and having a bearing, a hub in the bearing having opposed arms engaged with said front shoulders, and a spiral spring secured to the plate and having an end engaged with the rear shoulder, said depressed part being located spaced from the rear terminal of the bolt so that the latter provides a stop restricting movement of said end of the spring laterally of the plate and also a connection for remote retracting means for the bolt, the bottom of the depressed part being slidably seated against the case plate.

In testimony whereof I have hereunto signed my name to this specification.

FLETCHER D. GRUND.
